DESCRIPTION

FIG. 1 is a top side rear perspective view of a push broadcast spreader showing our new design;

FIG. 2 is a front elevation view of the push broadcast spreader of FIG. 1;

FIG. 3 is a rear elevation view of the push broadcast spreader of FIG. 1;

FIG. 4 is a first side view of the push broadcast spreader of FIG. 1;

FIG. 5 is a second side view of the push broadcast spreader of FIG. 1;

FIG. 6 is a bottom plan view of the push broadcast spreader of FIG. 1; and,

FIG. 7 is a top plan view of the push broadcast spreader of FIG. 1.

The broken line showing of the frame and wheels is included for the purpose of illustrating portions of the push broadcast spreader and forms no part of the claimed design.
